UNITED STATES PATENT OFFICE.

GEORGE W. ROBINSON, OF MILLVIEW, FLORIDA.

LOG-TURNER.

SPECIFICATION forming part of Letters Patent No. 315,073, dated April 7, 1885.

Application filed July 11, 1883. Renewed January 17, 1885. (No model.)

To all whom it may concern:

Be it known that I, GEORGE W. ROBINSON, of Millview, in the county of Escambia and State of Florida, have invented certain new and useful Improvements in Log Rollers and Turners; and I do hereby declare that the following is a full, clear, and exact description of the invention, which will enable others skilled in the art to which it pertains to make and use 5 the same, reference being had to the accompanying drawings, and to the letters of reference marked thereon, which form a part of this specification.

My invention relates to that class of machines employed in saw-mills for rolling logs upon the carriage and turning the same when so loaded.

It consists, essentially, of a casting or block slotted to receive the upright toothed stock of 20 the log-roller, and adapted to slide at right angles to the carriage upon a slotted bed-block in such manner as to carry with it said upright toothed stock, and prevent its teeth from coming in contact with the passing head-blocks.

25 In the accompanying drawings like letters refer to the same parts in each figure, and in the same Figure 1 is an end view of a saw-mill carriage with a section of the logway and the toothed bar or stock of a log-turner shown 30 in connection with my improvements. Fig. 2 is a plan view of a portion of the carriage, showing the top of the slotted casting or block through which the toothed stock of the log-turner is made to pass, the dotted lines showing 35 the position of the block in contact with a passing head-block; and Fig. 3 is a vertical cross-section, on the line xx , Fig. 2, of the slotted sliding block with its bed plate or block and a portion of the toothed stock of 40 the log-roller.

B B represent the frame-work of a saw-mill carriage, with a head-block, A, overhanging the carriage at the front end, in the usual way.

H is the logway upon which the logs are 45 rolled to the carriage.

E is the upright bar or stock of a log turner or roller, provided with the teeth c c c. It extends from underneath the floor of the mill up through the casting F, its bed-block G, 50 and the logway H, all of which are slotted to

receive it and to allow of its lateral movement at right angles to the length of the carriage. The block F is provided with the rounded or beveled end a toward the carriage, and is grooved upon its under and inner faces to receive the flanges g g, projecting laterally from the upper part of block G, upon which it slides horizontally at right angles to the carriage. The bed-block G is secured to the floor or some convenient part of the frame-work of 60 the mill, with its front end near the carriage. The beveled end a of the sliding block F overhangs the bed-block G in such manner as to be struck and thrust back by the passing head-blocks A of the carriage whenever the toothed 65 stock E is in its forward position. A pair of inwardly-projecting shoulders near the front end of the slot in block G prevent the toothed stock E from advancing beyond a certain point toward the carriage—a point at which the 70 teeth c c will just clear the edge of the carriage-frame B, as seen in Fig. 2. A similar pair of shoulders, d d, project inwardly near the front end of the slot in sliding block F, and prevent the stock E from advancing beyond them. 75

In using log rollers and turners as commonly constructed and operated, accidents are liable to occur, when the carriage is in motion, from the teeth in the stock E striking the overhanging ends of the head-blocks A as they pass. To meet this difficulty I employ the herein-described sliding block F, with its rounded end a projecting forward beyond a line connecting the front ends of the head-blocks whenever the toothed stock E is in its extreme forward position. As the head-blocks 80 A of the carriage pass the same they strike the rounded or beveled end a and thrust the block F back, carrying the stock E with it, to 85 a point where the teeth c c will clear the head-blocks, thereby preventing accidents or injury to the machine while the carriage and log-turner are both in motion. The block F sliding freely back and forth upon the bed-block G, the stock E can be readily advanced to its forward position when desired. 90

Having thus described my invention, what I claim as new, and desire to secure by Letters Patent, is— 95

1. In a log roller and turner, the combination of the toothed stock E with the slotted sliding block F, having the rounded or beveled end a, substantially as and for the purposes set forth.
2. In a log roller and turner, the combination of the slotted block F, having the beveled end a, and being adapted to slide freely back and forth upon the slotted bed-block G, together with the toothed stock E, substantially as and for the purposes set forth.
3. The combination, in a log roller and turner, of the block F, slotted to receive the toothed bar E, and adapted to slide at right

angles to the carriage upon the base-block G, 15 and prevent the teeth in the bar E from coming in contact with the passing head-blocks A of the carriage, together with toothed bar E and base-block G, substantially as and for the purposes set forth. 20

In testimony that I claim the foregoing as my own I affix my signature in presence of two witnesses.

GEORGE W. ROBINSON.
